FRAME CONSTRUCTION FOR RACKS WITH
ADJUSTABLE SHELVESJoseph St. Amour, Newmarket, N.H., assignor to Kingston
Manufacturing Co., Inc., Newfields, N.H., a corpora-
tion of New Hampshire

Filed Apr. 21, 1961, Ser. No. 104,591

1 Claim. (Cl. 211—147)

The present invention relates to storage and dispensing racks of the type commonly used in retail establishments operating on the self-service system. The particular object is to provide a frame and cooperating accessories permitting the ready adjustment of the relative positions and inclinations of supporting shelves through a series of small steps.

My invention will be well understood by reference to the illustrative embodiment shown by way of example in the accompanying drawings wherein:

FIG. 1 is a perspective of a unit storage rack;

FIG. 2 is a fragmentary elevation of a part of one of the front supports partly broken away and showing how the front edge of the shelf is supported;

FIG. 3 is a similar view showing how the rear edge is supported;

FIG. 4 is a perspective of the bracket or clip by which the rear edge of the shelf is engaged;

FIG. 5 is a horizontal section of the upright and bracket. The sectioning plane cuts the bracket along line 5—5 of FIG. 4;

FIG. 6 shows two aligned uprights with their webs and flange developed or opened out into a plane and showing the relationship thereto of the brackets; and

FIG. 7 is a schematic view showing how the brackets may be formed from a strip of metal.

In many retail establishments at the present day, more particularly those operating on the self-service principle, goods are stored on and taken by the purchaser from racks 8 of the general type shown in FIG. 1 and consisting of a terraced series of shelves. For the sake of simplicity only two such shelves, 10 and 12, are shown in the drawing but obviously there may be a number of superposed shelves of each type. The front edges of the shelves in a stack are usually set progressively further to the rear so that the forward portion of each shelf is exposed to permit inspection of the goods at the forward portion thereof, and to permit the customer to pick up the leading article in a row and take it away.

Columns of packages or articles are arranged on the shelves, ordinarily on tracks such as the track 14 on the shelf 10 or, in the case of the shelf 12 which stands at a low angle, a roller trackway 16. Only one track is shown in each case, but it will be understood that a number may be set side by side on the various shelves and each receives a column of goods which is replenished at the rear as articles are taken away at the front. A flange 18 at the front of each shelf makes a stop for the head of the column.

To provide for the progressive setting back of the front edges of the shelves their forward ends may be supported from rearwardly inclined members 20 and their rearward ends from vertical uprights 22 in the case of the shorter shelves 10, and 24 in the case of the longer shelves 12.

Only a single bay or section of the rack is shown in the drawings. It might be duplicated side by side and if extended toward the right in the figure the right-hand member 20, and uprights 22 and 24 would provide for the support of the opposed edges of two sets of shelves. That is, two bays would require only three sets of a member and two uprights, three bays four sets, etc.

The present invention relates more particularly to a

2

construction of frame providing for the support of shelves in desired positions of elevation and with desired angles of slope. In particular the purpose is to provide for a very fine range of adjustment. The situation is quite different from that of ordinary horizontal shelves, such as those in a bookcase where positioning of the shelves with a spacing varying by increments of, say, one inch is provided by a movable series of brackets inserted in vertical series of holes on one-inch centers. In particular it is desirable to be able to quickly shift one shelf relative to those on either side of it and to adjust its angle to facilitate or slow down the forward movement of the rows of goods on the tracks as their nature may require. A very slight change in the pitch may be required and the head room available with respect to other shelves and because of the types of packages which are to be supported may at times be very limited. Therefore an increment of adjustment much smaller than that provided in the bookcase is desirable, and this is provided by the construction of the present invention.

The sides of the shelves, as 10, may be formed by angle irons with vertically depending flanges 26 at their outer sides and extending between the inwardly facing flanges 20f of a front member 20 and 22f of a rear upright 22, 25 which flanges are in the same plane.

As seen in FIG. 2 the front ends of the shelves are supported by headed pins 28 projecting from flanges 26 and engaging in one of a series of bayonet slots 30 in the adjacent flange 20f of member 20. This provides a 30 pivotal connection and permits the shelf to lie at a variable angle determined by the point of support at the rear as on upright 22.

The supporting means for the rear of the shelf is shown in FIG. 3 and comprises brackets 30 movably and adjustably mounted on the adjacent flange 22f of upright 22 by means of an array of slots 32 in the latter flange as will more fully appear. In FIG. 3 the major portions of the brackets are at the further side of the flange of upright 22 and appear dotted in the figure.

40 The bracket (see FIG. 4) has two horizontal shoulders 34 to underride the vertical flange 26 of the side member of the shelf, which, when sloped, rests on the forward one of these shoulders, and a tongue 36 arising from these shoulders overlies the flange 26 which latter is confined between the tongue and the inwardly facing flange 22f of the channeled upright 22. Projecting beyond these shoulders are downwardly facing hooks 38 which pass through selected slots 32 in the flange of the upright and interlock with their lower edges. The dimensions of the throats 39 of the hooks is substantially equal to the thickness of the flange of the upright. There are two only of these hooks, one on each side of the bracket, which are vertically offset for reasons which will appear. The brackets are identical. No rights and lefts are required.

50 55 FIG. 7 shows a strip of metal with the outlines of blanks for the brackets indicated thereon and shows how they may be formed from such a strip, rolled into shape and severed one from another.

60 The channel uprights as 22 are of identical construction (not rights and lefts) and if faced the same way, open side forward in the figures, can serve indifferently as right hand, intermediate or left hand uprights. However considered alone they are not completely symmetrical but the right hand facing flange 22f is different (in the arrangement of slots therein) from the left hand facing flange 22f.

65 In FIG. 6 the point of view is from the front and we are looking toward the open side of channeled uprights 22. The figure illustrates the flanges 22f of the channel as if folded back into the plane of the web and what we see is the interior of the flanges. At right and left of the

figure we see simultaneously the interiors of the two uprights 22 which are in fact at opposite sides of the shelf. In a single bay structure like FIG. 1 the slotted areas at the extreme right and left would not be utilized for connection of the shelf to the uprights.

Referring to FIG. 6 we see at the left of the figure but nearer the center the right facing flange 22f of the left upright 22. The arrangement of slots therein is identical with the right flange of the right upright 22 at the extreme right of the figure. The arrangement of slots in the left facing flange of the left upright and the right facing flange of the left upright is the same but differs from that of the other two flanges. The shelf therefore is received between two flanges which differ in the arrangement of slots, the arrangements being those of the two adjacent arrays of the central portion of FIG. 6.

Each flange is pierced by three vertical columns of aligned slots 32 with their elements staggered. That is the slots are disposed in echelon to provide ranks of aligned slots at an inclination to the vertical as indicated by the lines 40 at the left of FIG. 6 which pass through the centers of the slots of two such ranks. The vertical spacing of the centers of adjacent pairs of slots approximates their lengths. Therefore two horizontally aligned slots have their upper and lower ends substantially coinciding with the lower and upper ends of slots at respectively higher and lower levels. However as will appear from the figure the inclined ranks of the array in the left hand facing surface of the upright at the right are offset vertically from the ranks in the opposite right facing surface of the member at the left.

Referring to FIG. 6 we see at left center in full lines a bracket 30 with its hooks 38 received in the intermediate and lower slots of an inclined rank, respectively in the center (viewing the figure) and right vertical columns. If the hooks are shifted upwardly and to the left in the rank, the brackets take the dotted line position with the hooks received in slots of the left hand and center vertical columns. The bracket is thus adjusted to positions spaced by little over half the vertical distance between the slots in a column.

When a bracket is turned around a vertical axis the upper and lower hooks exchange sides. The offsetting of the ranks in the oppositely facing arrays permits the brackets to be assembled with the opposite upright at

exactly the same elevation and directly opposite although the hooks engage in vertically disaligned slots respectively of two vertical columns which columns as such respectively lie in the same two vertical planes.

The capacity for close adjustment is obtained by the cooperation of the particular form of bracket which has two only vertically offset hooks with the closely arranged slots in diagonal ranks.

I claim:

A framed construction comprising at least one pair of uprights supporting the ends of a transverse shelf-like element extending between the uprights, the uprights of the pair having right and left facing portions between which said element is received, each upright consisting of a thickness of metal having three vertical columns of vertically elongated slots disposed in echelon to provide ranks of aligned slots at an inclination to the vertical, the vertical spacing of the centers of adjacent pairs of slots in a rank approximating their lengths, the ranks of the right facing columns being offset vertically from the ranks of the left facing columns by a distance equal to the vertical distance between adjacent slots of a column, members for supporting the transverse element from the uprights, each member having a portion to engage from below the transverse element and two only downwardly-opening projecting hooks each of a size to pass through a slot and engage around the lower edge thereof, the hooks being spaced horizontally and vertically to correspond with the horizontal and vertical spacing of adjacent slots in a rank to permit them to be fitted into any such pair of adjacent slots in the array to provide in connection with both uprights for vertical adjustment of the engaging portions in a series of positions spaced by half the vertical distance between the adjacent slots of a column.
